CLAIM

The ornamental design for an eye mask, as shown and described.

DESCRIPTION

FIG. 1 is a front, right and top perspective view of an eye mask, showing my new design;

FIG. 2 is a rear, left and bottom perspective view thereof;

FIG. 3 is a front, right and top perspective view thereof, shown in a position of use;

FIG. 4 is a rear, left and bottom perspective view thereof, shown in a position of use;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof; and,

FIG. 11 is an enlarged detail view of portion 11 encircled in FIG. 4.

The broken lines shown in the drawings illustrate portions of the eye mask that form no part of the claimed design.

The dot-dash broken lines depict the boundaries of the enlargements that form no part of the claimed design.

1 Claim, 11 Drawing Sheets
